DESIGN FOR A SLIPPER OR SIMILAR ARTICLE

Kenneth Keyes, New York, N. Y.

Application May 21, 1946, Serial No. 129,936

Term of patent 7 years

(Cl. D7—7)

To all whom it may concern:

Be it known that I, Kenneth Keyes, a citizen of the United States of America, residing in New York, county of New York, and State of New York, have invented a new, original, and ornamental Design for a Slipper or Similar Article, of which the following is a specification, reference being had to the accompanying drawing, forming part thereof.

The figure on the drawing is a perspective view of a slipper or similar article showing my new design. The opposite side presents substantially the same appearance as the side shown.

The essential features of my design for a slipper of the specific type as shown, is characterized by the placement of two transparent straps of substantially the same width throughout, across the sole portion, the outer edges of the straps being ornamented in a manner as illustrated.

I claim:

The ornamental design for a slipper or similar article, substantially as shown and described.

KENNETH KEYES.
